CLAIM

What is claimed is the ornamental design for an asymmetric escutcheon chamfer, as graphically illustrated and described herein.

DESCRIPTION

FIG. 1 is a front view of an asymmetric escutcheon chamfer embodying our new design. Note, the accompanying latching pin which would attach to a swinging door, or sliding drawer is not illustrated in this view for clarity;

FIG. 2 is a left-front isometric view of the asymmetric escutcheon chamfer, with the latching pin clearly apparent; FIG. 3 is a right-front isometric view of the asymmetric escutcheon chamfer, with the latching pin shown;

FIG. 4 is a left-front isometric view, door pin shown exploded;

FIG. 5 is a right-front isometric view, door pin omitted for clarity;

FIG. 6 is a top view of the asymmetric escutcheon chamfer. This view does not provide a view of the feature described by this design patent;

FIG. 7 is a right side view of the asymmetric escutcheon chamfer. This view does not provide a view of the feature described by this design patent but provides anecdotal context nonetheless;

FIG. 8 is a left side view of the asymmetric escutcheon chamfer. This view does not provide a view of the feature described by this design patent but provides anecdotal context nonetheless;

FIG. 9 is a bottom view of the asymmetric escutcheon chamfer. This view does not provide a view of the feature described by this design patent;

FIG. 10 is a bottom left isometric view showing the asymmetric chamfer escutcheon feature which accepts the interfacing pin on the adjacent door to be secured;

FIG. 11 is a bottom right isometric view showing the asymmetric chamfer escutcheon feature described herein; and,

FIG. 12 is an isometric view of installed latch showing the intended installation with a cupboard door and compartment secured by the latch device.

The broken (dashed) lines showing the locking housing in FIGS. 1-12 represent environmental matter and form no part of the claimed design.
